Inventor:

UNITED STATES PATENT OFFICE.

JOHN H. ROBERTSON, OF PLATTEVILLE, WISCONSIN.

FOOT-REST.

1,218,120.

Specification of Letters Patent.

Patented Mar. 6, 1917.

Application filed June 27, 1912. Serial No. 706,266.

To all whom it may concern:

Be it known that I, JOHN H. ROBERTSON, citizen of the United States, residing at Platteville, in the county of Grant and State 5 of Wisconsin, have invented certain new and useful Improvements in Foot-Rests, of which the following is a specification, reference being had therein to the accompanying drawing.

10 This invention relates to an improvement in attachments for hot air registers and the object of the present invention is the provision of a simple and efficient device for use in conjunction with the ordinary hot 15 air register which is so constructed that it may be used as a foot rest or to support articles of various kinds for the purpose of drying them or keeping them warm.

A further object of the present invention 20 is the provision of a device of this character which is so constructed that it may, when desired, be removed from its position adjacent the register without in any way defacing or altering the appearance thereof.

25 Other objects of the invention will be apparent from the detailed description hereinafter when read in connection with the accompanying drawings forming a part hereof, wherein a convenient embodiment of 30 the invention is illustrated, and wherein like characters of reference refer to similar parts in the several views.

In the drawings:

Figure 1 is a perspective view of the improved foot rest, showing in part the shelf which is adapted to be supported thereon;

Fig. 2 is a cross section, showing the foot rest in position with a shelf supported thereon;

40 Figs. 3, 4 and 5 are detail views of the wall plates and one of the covers for the sockets therein;

Fig. 6 is a front elevation of a register, the foot rest being shown removed therefrom;

Fig. 7 is a detail view showing the construction of the frame of the foot rest;

Fig. 8 is a side elevation of the improved foot rest and a cabinet supported thereon, 50 and

Figs. 9, 10 and 11 are detail views of the construction shown in Fig. 8.

Referring now more particularly to the drawings, A designates a hot air register 55 which may be of any well known type. B

designates the foot rest which comprises a frame formed of a pair of side members C C which are adapted to be secured adjacent the sides of the register A and to project in front of the same, and bars D D 60 which rigidly connect the upper portions of said side members. The bars D D are positioned in front of the hot air register A and are spaced from each other, the bar nearest the register being preferably positioned a slight distance above the outermost bar. The bars D D may be of any suitable form and construction. Conveniently, however, I form said bars of tubes and secure the same between the side pieces C C of the 70 frame of the foot rest by means of suitable tie rods d d which pass through said tubes and through the side members of the frame, the side members and the bars being rigidly united by means of nuts threaded on the 75 ends of said tie rods. By means of this construction tubes of any desired lengths can be utilized in connection with the side frames to make the foot rest the proper width for use in connection with registers 80 of various sizes. The foot rest B may be supported in any suitable manner, but I prefer to support the same in such a way that it may be readily removed from its position adjacent the register when desired. 85 To this end, the wall at the sides of the register A and the adjacent portions of the side pieces C C of the foot rest B are provided with coöperating interengaging 90 portions enabling the foot rest to be readily secured in position or removed without the necessity of employing any screws or similar fastening devices. In the embodiment of the invention illustrated, wall plates E are secured by suitable fastening screws or 95 other means at the sides of the register A adjacent the upper and lower portions of the register. Each of the wall plates E is provided with a socket therein having a front wall in which is formed a slot e having an enlarged upper end. The rear portions of the side pieces C C of the foot rest B are provided with portions which are adapted to directly contact with the front walls of the sockets in the wall plates E 100 and from which project studs e having enlarged heads e' which are of a size to pass through the enlarged portions of the slots e in the wall plates but are too large to pass through the narrow portions of said slots. 110

From the construction thus described it will be seen that by introducing the heads c' of the studs c projecting from the side pieces of the foot rest B into the enlarged portions 5 of the slots e , of the wall plates E , and lowering the foot rest B , said frame will be secured in position. The front walls of the sockets in the wall plates E are preferably provided on their rear surfaces adjacent 10 the narrow portions of the slots e with wedge shaped ribs e' which are adapted to coöperate with the heads c' of the studs c projecting from the side pieces of the foot rest to draw said side pieces of the foot rest 15 tightly into engagement with the wall plates as the foot rest is lowered. While I have illustrated the wall plates as formed separate from the register A , it is obvious that such plates may, if desired, be made integral 20 with the front plate of the register.

In securing registers within walls, the general practice is to utilize a register of a size to fit snugly between two of the relatively narrow studding pieces in the wall 25 and as the front plate of the register is generally somewhat wider than the frame thereof, it will be seen that there is a comparatively small space left at the outside of the front plate in which to secure the wall plates 30 so that the securing screws therefor will pass into the studding as is desirable. To insure proper securing of the upper wall plates, I conveniently form such plates with a main body portion which is adapted to be secured 35 directly alongside of the front plate of the register and with an upper inclined portion e^2 which is adapted to extend above the upper end of the front wall of the register and inwardly of the side thereof, the inwardly 40 extending portion of said inclined portion e^2 being provided with a suitable opening therein for a fastening. This construction insures a firm anchorage for the wall plates as the fastening screws in the inwardly extending 45 portions of the widened upper ends e^2 thereof will pass through the central portion of the studding pieces at each side of the register. In the construction shown in the drawings, the lower wall plates are secured 50 to the base board, but when the register is positioned above the base board, the lower wall plates will be similar to the upper plates just described.

The studding pieces are always placed 55 just sixteen inches apart, center to center. From this arrangement it follows that because of the peculiar construction of the wall plates with the two fastening screws passing through the apertures in the upper 60 wider portion of the plates the same may be employed in connection with various widths of registers and within certain limits, either the two inside screws or the two outside screws securely engaging the studding. 65 With the wall plates as shown, and with any

width of register front from twelve and one-half inches wide to seventeen inches wide, either the inside or outside screws will go into the studding and as it is only necessary for one of these screws in each wall 70 plate to go into the studding in order to make a secure fastening this construction makes the foot rest adaptable to practically all the different widths of registers that are on the market by simply using the different 75 lengths of tubes and tie-rods.

To improve the appearance of the wall plates E when the device is detached therefrom, I preferably provide cover plates F for said wall plates. Each of said cover plates 80 F comprises a body of a size to overlie the front wall of the socket formed in one of the wall plates E and completely covering the slots e therein from which body portion extends a stud f having an enlarged head, said 85 stud being similar in construction to the studs c which extend from the side pieces C of the frame B , so that the cover plates may be, when desired, secured in position in substantially the same manner as heretofore 90 described in connection with the frame B . The outer surface of the cover plates F may be ornamented, if desired, in any suitable manner.

G designates a shelf which may, when 95 desired, be used in conjunction with the foot rest B heretofore described, said shelf comprising a metal body portion having an open central portion to permit the passage of the hot air therethrough. Depending 100 from the underside of the shelf G adjacent the rear edge thereof are a pair of brackets G' which enable the shelf to be detachably secured to the foot rest B . The brackets G' are provided in the rear ends thereof 105 with slots g which are adapted to receive the innermost bar D of the foot rest B when the shelf is in position thereon. Each of the brackets G' is also provided with a portion g^2 which is adapted, when the shelf 110 is in position, to rest directly upon the outermost bar D of the foot rest B and with a portion g^2 which is adapted to lie directly in rear of the outermost bar D of the foot rest B , thus preventing outward movement 115 of the shelf relative to the register A . To remove the shelf it is only necessary to elevate the outer end thereof a sufficient distance to withdraw the portion g^2 of the brackets from in rear of the outermost bar 120 D of the foot rest when by an outward movement the shelf can be removed. The shelf B is useful to support articles of various kinds when it is desired to either dry the same or to keep the same warm. In many 125 instances, however, better results may be secured when it is desired to use the device as a support for articles to be dried, to remove the shelf and to use the bars D of the foot rest B as a support for the articles. 130

These bars are particularly efficient for supporting shoes and other articles of wearing apparel.

In lieu of the shelf G the foot rest B 5 may be used to support a cabinet for keeping foods and the like warm and in Figs. 6 and 7 of the drawings, I have illustrated a cabinet of this character. In the construction disclosed in this figure, H designates 10 a cabinet, the bottom of which is conveniently provided with apertures therein to admit the heated air thereto from the register and the upper portion of which is provided with suitable openings to permit the air to pass outwardly therefrom. Depending from the bottom plate of the cabinet H are a pair of brackets H', the lower edges of which are provided with upwardly extending slots h therein which are adapted 15 to receive the rods D D of the foot rest when the cabinet is lowered thereon. To prevent accidental displacement of the cabinet, and to hold the same firmly upon the foot rest B, means is conveniently provided 20 for connecting the upper portion of the cabinet with the adjacent part of the wall. In the embodiment of the invention illustrated, I have shown, for this purpose, a button I which is secured to the wall adjacent the 25 cabinet and is provided with an enlarged head which is spaced from the wall. Secured to the cabinet and projecting rearwardly therefrom is a bracket K, the outer

end of which is provided with a pair of separated arms k having inturned portions 35 k' which are adapted as the cabinet is lowered onto the bars D D of the frame, to move behind the enlarged head of the button I secured to the wall and thus hold the cabinet against outward movement. 40

While I have illustrated in the accompanying drawings, a convenient embodiment of the invention, it will be understood that many changes may be made to the form and construction therein shown without departing from the spirit and scope of the invention as defined in the appended claim. 45

I claim:—

An attachment for hot air registers comprising a frame composed of spaced side pieces having cross bars arranged therebetween, means for supporting said side pieces adjacent the register, and a shelf having depending brackets, each of which have oppositely opening recesses therein for engagement with the front and rear portions of the cross rods, whereby the shelf may be moved from the cross rods upon an upward and forward movement. 55

In testimony whereof I affix my signature 60 in presence of two witnesses.

JOHN H. ROBERTSON.
